UNITED STATES PATENT OFFICE.

CLEMENT MARIE TIRARD, OF PARIS, FRANCE.

HAT-POUNCING MACHINE.

SPECIFICATION forming part of Letters Patent No. 691,018, dated January 14, 1902.

Application filed September 10, 1901. Serial No. 74,931. (No model.)

To all whom it may concern:

Be it known that I, CLEMENT MARIE TIRARD, a citizen of the Republic of France, and a resident of 11 Rue Grange Batelière, Paris, France, (whose post-office address is as above,) have invented certain new and useful Improvements in Hat-Pouncing Machines; of which the following is a specification.

This invention relates to improvements in hat-pouncing machines, and has for its object to provide improved mechanism for pumicing or glass-papering the same, commonly termed "pouncing."

In the accompanying drawings, Figure 1 is a plan view of the mechanism as a whole at the moment of the commencement of the operation of pouncing a hat. Fig. 2 is a front elevation of the mechanism at another phase in the operation. Fig. 3 is a corresponding plan view. Fig. 4 is a side elevation of the same mechanism at the termination of the pouncing operation. Fig. 5 is a corresponding plan view. Fig. 6 is a detail view of the pouncing member and of its operating mechanism, and Fig. 7 is a front elevation of this pouncing member.

My improved machine comprises, essentially, a pouncing member operated by means of an appropriate motor imparting to it a movement adapted to suitably effect the friction upon the surface of the hat under conditions resembling those of handwork, and this pouncing member, provided with its own driving mechanism, is guided by other mechanism, so that it passes over every point of the surface of the hat, to which a movement of rotation is imparted.

The hat 1 is mounted upon a finishing-form 2 in the manner usual in all hat-finishing machines, and this form 2 is rotated in such a manner that notwithstanding the shape of the hat this latter always rotates circularly with respect to the point at which it is in contact with the pouncing member. Briefly, the operating device is similar to that employed in lathes for turning oval objects. With this object the finishing-form 2 is rigidly connected to a shaft 4 by means of suitable catches 3. This shaft is rigidly connected to a slide 5, mounted in a slideway 6, fixed to the driving-shaft 7, by means of which the motive power is transmitted. The lateral

edges of the slide 5 are in contact with a fixed circular way 8, mounted upon the general framework and which is eccentric with respect to the driving-shaft 7, which latter is operated by suitable transmission-gear 9.

The pouncing member consists of a support 10, upon which is arranged the sheet of pouncing material 11—such as glass, paper, or linen, for example—its surface being slightly convex. Between the sheet of pouncing material and its support 10 a sheet of felt or similar material is interposed. The support 10 is rigidly connected with a plate 12, mounted upon two eccentrics 13 14, of which the axes 15 16 are journaled in the wall 17 of a box or frame 18. Upon the axes 15 and 16 are rigidly fixed two pinions 19 and 20, connected by means of an intermediate pinion 21. In addition to the pinion 20 the axis 16 carries a second pinion 22, meshing with the pinion 23 of a small electric motor 24. It follows from this arrangement that when the electric motor 24 is operative the pouncing member 10 assumes a movement such that each of its points describes a small circle owing to its eccentric driving. It should be noticed that the sheet of glass paper or the like 11 is mounted by means of a flat spring 25, maintained in lugs 26, mounted upon the support 10. The whole device, constituted by the pouncing member and its motor mounted upon the box-frame 18, is fitted into a fork 27, provided with a suitable handle 28. This fork 27 is rigidly connected to an axis 29, running on ball-bearings in a sleeve 30, adjustably attached to a base 31, to which latter is pivoted a second fork 32, which is also journaled upon a shaft 33 and terminates in a handle 34. The fork 27 is mounted in its sleeve in such a manner as to render the point of attachment of the frame eccentric to the axis 29, and thus regulate the position of the frame by reason of its own weight. The second fork 32 is provided with a part 35, comprising two projections 36, serving for the reception of a shaft 37, to one of the extremities of which is fixed an arm 38, while its other extremity is provided with a pawl 39. Upon the said shaft 37 and between the two projections 36 is engaged a spiral spring 40. The part 35 is also provided upon its lower face with a ring 41, to which is attached a counterweight 42.

The connection between the pouncing device and the driving-shaft is effected in the following manner: The shaft 35 is mounted in a fork 43, rigidly connected with a plate 44, carrying a socket 45. Upon this plate 44 is fixed another plate 46, to which is attached a connecting-rod 47, which is journaled upon a toothed wheel 48. This latter is mounted loose upon a cylindrical hub 49, carrying a shaft 50, which is journaled upon the general framework. The point upon which the toothed wheel 48 is mounted is eccentric with respect to the shaft 50. To the hub 49 is fixed a handle 51, by means of which it may be rotated. Upon the framework of the machine and beneath the handle 51 is arranged a flat spring 52 in the form of the arc of a circle, which comprises a stop-notch 53, serving to maintain the said handle 51 in a predetermined position. The gear-wheel 48 is provided upon its lower face with a projection 54, adapted to come into contact with the spring 52. In addition to the handle 51 the hub 49 is provided with an arm 55, to which is attached a counterweight 56. The connecting-rod 47 carries a stud 57, adapted to act upon a sector 58, mounted upon an axis 59, the extremity 60 of which is adapted to come in contact with the arm 38. The gear-wheel 48 is in engagement with a pinion 61, rigidly connected with a pinion 62, which meshes with a gear-wheel 63, fixed to a shaft 64, driven from the shaft 7 by means of screw transmission 65.

The operation of this mechanism is as follows: In the first place it should be remembered that the pouncing member receives from its electric motor a movement which, as above stated, reproduces that of hand-pouncing, but which is more uniform. It is therefore necessary to cause this member to pass over all points in the surface of the hat, and this is what the mechanism above described effects. It has also been pointed out that there is imparted to the hat a movement of rotation such that notwithstanding its oval shape it always rotates circularly with respect to the pouncing member. The pouncing member as a whole is balanced by means of a counterweight 42, whereby the pressure of this part upon the hat may be regulated as desired. The operation of the pouncing member upon the hat consists, independently of the movement imparted to the part itself by means of its electric motor, of a travel over the surface of the hat, comprising a forward travel and a return travel. When the hat has been placed upon the form, the pouncing member is engaged by means of the handle 28 with the part 35 by the intermediary of the pawl 39. The eccentric hub 49 is then displaced by means of the handle 51, so as to cause the gear-wheel 48 to engage with the pinion 61, and consequently with the driving-shaft 7. Fig. 1 represents the apparatus in this condition. The machine having been started, the pouncing member is dis-

placed slowly in the direction of the arrow α along a generating line of the hat. The pouncing member is thus brought to the brim of the hat, Fig. 3. Then owing to the movement of the connecting-rod 47, actuated by the gear-wheel 48, the pouncing member returns in the direction of the arrow γ , but passes beyond the point from which it started and proceeds to the axis of the hat. The object of this peculiar operation is that the pouncing member may not pass more than once over the top of the hat. This peculiarity is only due to special adjustment, and it is of course possible by adjustment of the connecting-rod 47 and of the plate 46 to cause the pouncing member to start from any desired point of the hat. When the pouncing member has completed its return travel, the connection with the driving-shaft is interrupted and the pouncing member is separated from the hat, while at the same moment the electric motor stops. This cessation of the operation is effected in the following manner: Shortly before the complete revolution of the gear-wheel 48 the stud 57 of the connecting-rod 47 acts upon one end of a pivoted lever 58, pivoted to the plate 46 at 59. (See Fig. 5.) The other end of this lever 58 has a hooked end 60, which bears against the arm 38 below its point of pivot to the shaft 35, and thus throws its upper end, with its shaft 37 and catch 39, out, disengaging the catch from the part 31 and allowing the pouncing apparatus to fall backward into the position shown in Fig. 4 by its own weight. The spring 40 returns the catch to its normal position when the lever 58 is released. Figs. 6 and 7 best illustrate the catch mechanism detached from the forks 43, which by reason of the overhang of this group of parts causes the device to separate from the hat and assume the position represented in Figs. 4 and 5. The projection 54 of the gear-wheel 48 then acts upon the spring 52, releases the handle 51 and the hub 49 by reason of its eccentricity with respect to the gear-wheel 48 and of the rotation of this latter, and rotates until this gear-wheel 48 is disengaged from the pinion 61, whereupon the operation ceases. The treatment of the hat is then completed. The duration of this operation may be regulated at will by the ratio of the pinions 61 and 63. At the same time that the operation of the device ceases the electric motor stops. In order to produce this result, there is arranged at a suitable point upon the machine an interrupter, which automatically closes the circuit when the machine is started and opens it when the machine is stopped.

I may of course introduce into my machine many constructional modifications whereby its essential characteristics are not altered. As regards the pouncing member I would point out that I do not wish to confine myself to its operation by means of an electric motor. I have indicated this method of actua-

tion because it is the most practical; but it is obvious that other methods may be employed—such, for example, as a small compressed-air machine. I would also state that 5 this pouncing member may be employed with any kind of mechanism other than that above described which is adapted to cause it to pass over the entire surface of a hat.

I claim as my invention—

10 1. A hat-pouncing machine, comprising a pouncing member, eccentrics on which it is mounted, a frame therefor and a prime motor in the frame to drive the eccentrics, substantially as described.

15 2. A hat-pouncing machine, comprising a pouncing member, a frame therefor, forks in which the frame is mounted, shafts in the frame adapted to move the member, and an independent prime motor carried by the frame 20 to operate the shafts, the said member being on one side of the forks and the motor on the other, substantially as described.

25 3. A hat-pouncing machine, comprising a pouncing member, a frame therefor, mechanism carried by the frame to operate the said member, forks to support the frame, said frame being mounted therein eccentrically to the point of support of the forks, substantially as described.

30 4. A hat-pouncing machine, comprising a pouncing member, a frame therefor, a prime motor in the frame, a pivoted base for the frame, a latch therefor, and mechanism to move said base around the hat to be pounced, 35 and against the hat when the base is latched down, substantially as described.

5. A hat-pouncing machine having a horizontal shaft carrying the hat, a rotary pouncing member, substantially vertical, a frame 40 therefor, a prime motor in the frame and means for traversing the frame with the vertical member from the crown to the brim and back, as described.

45 6. A hat-pouncing machine having a horizontal shaft carrying the hat, a pouncing

member, a pivoted frame therefor, a prime motor on said frame, means for moving the frame from the crown to the brim and back again, and a latching means to latch the frame into position to bring the pouncing 50 member into substantially vertical position, substantially as described.

7. A hat-pouncing machine, comprising a frame carrying a movable pouncing member, a gear-wheel, a connecting-rod connecting 55 said frame and wheel, said wheel being eccentrically mounted, a second gear-wheel, means for throwing said wheels into gear, whereby the frame is caused to travel from the crown to the rim and back again, and automatic means to throw the wheels out of gear at this stage, substantially as described.

8. A hat-pouncing machine, comprising a frame, a movable member and a prime motor therein, a pivoted base for the frame, a latch 65 for the base, gearing to move the frame and base from the crown to the rim and back again and means to automatically release the latch at this stage, substantially as described.

9. A hat-pouncing machine, comprising a 70 frame, a movable member, a pivoted base in which the frame is eccentrically mounted, an eccentrically-mounted gear-wheel, a connecting-rod, means for throwing said gear into mesh with another gear-wheel, a latch mechanism for the base and means for automatically throwing the gears out of mesh and releasing the latch upon the travel of the pouncing member from the crown to the rim and back, whereby the movement of the base is 75 stopped and the frame is allowed to fall back free of the hat, substantially as described.

In testimony whereof I have signed my name to this specification in the presence of two subscribing witnesses.

CLEMENT MARIE TIRARD.
